UNITED STATES PATENT OFFICE.

SUSAN GREIG AND MARY MAWSON, OF TORONTO, CANADA.

SKIRT EVENER AND MEASURER.

No. 820,567.

Specification of Letters Patent.

Patented May 15, 1906.

Application filed July 3, 1905. Serial No. 268,196.

To all whom it may concern:

Be it known that we, SUSAN GREIG and MARY MAWSON, gentlewomen, residing at the city of Toronto, in the county of York, in the

Province of Ontario, Canada, have invented certain new and useful Improvements in Skirt Eveners and Measurers, of which the following is a specification.

Our invention relates to improvements in skirt eveners and measurers; and the objects of our invention are to devise a device of cheap and simple construction by means of which a lady's skirt may be marked so that when made to this marking it will hang evenly and at the required distance from the floor, and, further, that the time taken to mark a skirt and the inconvenience given to the customer shall be as little as possible; and it consists, essentially, of a stool or low table, a flat oval marking-ring, supports for the marking-ring, a frame to which the supports are fastened, crank and chain-gear for lifting and lowering the frame, supports for the chain-gear, ratchet-wheel and stop to hold the frame in any position, a scale suitably graduated fastened to the side of the table, and a pointer attached to the frame to engage with the graduated scale, designed to register the distance the marking-ring is raised, the various parts being constructed and arranged in detail as hereinafter more particularly explained.

Figure 1 is a perspective view of the device, showing the top broken away to exhibit construction of the device. Fig. 2 is a front view of the device.

In the drawings like letters of reference indicate corresponding parts in each figure.

A is a stool or low table, which is made to stand about eighteen inches from the floor.

B is a flat oval marking-ring with a sharp outside edge B', designed to conform to the shape of the bottom of a lady's skirt and supported above and in a plane parallel to the top of the stool A by the supports B², which pass through the top of the stool.

C is a frame which is composed of two bars C², to which the supports B² are fastened, and two cross-pieces C', as shown in Fig. 1.

D is a chain-gear comprised of a sprocket-wheel D', which is mounted on and secured to the shaft F, a second sprocket-wheel D², pivoted to a support E, which is secured to the top of the stool, and a chain D², which is secured to the cross-pieces C' by the lugs C³, the whole being designed to lift or lower the

frame C by simply turning the handle F', which is secured to the shaft F and in this way moves the oval-shaped ring above or to the level of the top of the stool. 60

G is a graduated scale which is secured beneath the top of the stool.

H is a pointer which is secured to the bar C², connected to the marking-ring B in such a manner that it rises therewith and registers 65 on the scale G the height to which the oval-shaped ring has been lifted above the top of the stool.

J is a ratchet which is secured to the shaft F, with a stop K supported on a side plate K', designed to hold the oval-shaped ring in any desired raised position. 70

Having now described the construction of our invention, we shall now proceed to describe the method of using the same. The 75 customer stands on the stool inside of the oval marking-ring, so that the skirt hangs over the ring. The dressmaker now raises the oval marking-ring above the level of the top of stool to the distance the customer desires her skirt to be made to hang from the floor, this distance being indicated by the pointer H and scale G. The customer now stands in her natural position, while the dressmaker marks the skirt at the required 80 height by pressing the skirt with a piece of chalk against the sharp edge of the oval marking-ring and in this way marks the skirt, so that when made to this marking it will hang even and at the required distance 85 from the floor. 90

It will be seen that by a device such as we have described one is able to mark a dress for making in a very few minutes and with no inconvenience to the customer or trouble to 95 the dressmaker, and, further, a skirt can be marked so that when made to this marking it will hang evenly and at the required distance from the floor, no matter the deformity of the customer. 100

What we claim as our invention is—

1. In a device of the class described, the combination with a stool, of a flat oval ring above the top of the stool, supports extending down through the top of the stool to support the ring, bars fastened to the lower end of the supports, cross-pieces connecting the bars and a chain-gear fastened to the cross-pieces to lift or lower the supports, as and for the purpose specified. 105

2. In a device of the class described, the combination with a stool, of a flat oval ring,

supports to hold the ring above and in a plane parallel to the top of the stool, a frame to which the supports are fastened, a chain-gear to lift the frame so that the oval ring shall always be in a plane parallel to the top of the stool, and a registering device to register the height to which the ring has been lifted, as and for the purpose specified.

3. In a device of the class described, the combination with a stool, of a flat oval ring, supports to hold the ring, a frame to which the supports are fastened, a chain fastened to the frame, sprocket-wheels to engage with the chain, supports to hold the lower sprocket-wheel, a crank and shaft to turn the upper sprocket-wheel, a ratchet-wheel secured to

the shaft, and a stop to hold the ratchet-wheel in any position, as and for the purpose specified.

4. The combination with the substantially flat oval ring having a fine outer edge and adjustably supported, of the stool proper arranged to extend laterally beyond the outer edge of the ring, whereby the height of the skirt above the floor, when marked, may be seen as specified.

SUSAN GREIG.
MARY MAWSON.
